BABY'S BOTTLE HOLDER

Jay S. Swaim, Los Angeles, Calif.

Application August 27, 1945, Serial No. 612,769

5 Claims. (Cl. 248—104)

1

This invention relates to devices for supporting a baby's nursing bottle.

In the past it has been quite difficult to find a baby's nursing bottle holder which meets the requirement of minute adjustment of the bottle's nipple in relation to the child's mouth whereby when the child turns its head and loses the nipple it is readily found when the head is turned again bringing the mouth of the child in position again to grasp the nipple. Sometimes this adjustment necessitates only a slight change in the position of the bottle. Again, when the child has finished nursing from the bottle to provide a single adjustment for retracting the bottle sufficiently to remove it from the child's grasp.

To accomplish the aforesaid more advantageous adjustments of the bottle support is an important object of the invention.

More specific objects pertain to the provision of a spiral coil of wire adapted to enclose a nursing bottle and capable of being screwed either vertically upward or downward in relation to a suspending means carried by side rails of the crib; to provide for vertical adjustment of the spiral coil by the bending of pliable means located adjacent the ends of the bottle supporting means spanning the crib; to provide in a device of the character stated which is safer to use, which is more quickly adjustable and stable for all practical purposes; by either screwing the bottle holder upwardly or downwardly in its supports the bottle may be quickly inverted thus permitting no drip from the nipple between nursing periods; and to provide improved equalizer means as a part of the construction to insure that the nursing bottle will always maintain a perpendicular relation to the suspending means that supports it.

Other objects, advantages and features of invention will hereinafter appear.

Referring to the accompanying drawings wherein is shown what at present is deemed to be a preferred embodiment of the invention;

Fig. 1 is a perspective view of the device in its operative position, fragments of the side rails of the crib being shown in section.

Fig. 2 is a fragmentary enlarged side elevation of the device shown in Fig. 1 with a nursing bottle included in the view. A portion of the suspending means at the right of the view being broken away to show interior construction, dotted lines indicating parts in another adjusted position.

Fig. 3 is a fragmentary plan view of the device shown in Fig. 2.

Referring in detail to the drawing, the device

2

comprises a bottle-holding coil 5 which is supportable between the side portions 6 of a baby crib by means of a pair of elongated spring members 7 and 8.

Said coil which forms the bottle holder, is of a sufficient diameter to contain the bottle 9, having a downwardly directed neck portion 10 furnished with a nipple 11, the lower part of said bottle-holding coil being contracted at 12 around the neck of the bottle to keep the bottle from dropping out of the lower end portion of the coil, which coil portion, however, is of a sufficiently large diameter to allow the bottle neck to extend downwardly therethrough.

The inner end of the spring member 7 is shown attached by an eye 14 directed to one of the turns of the coil 5 at about the mid-length of the latter, but an attaching or equalizer clip 15 is provided as a means for attaching the inner end of the spring member 8 to that side of the coil 5 which is diametrically opposite to the attachment of the spring member 7 thereto. Said clip 15 consists of a small flat, vertically disposed plate having its inner edge portion (in relation to the coil 5) provided with an upper aperture 16 and with a lower aperture 17, adjacent turns of the coil 5 passing through these apertures. The spring 8 is provided at its inner end with an eye 19 led through an eye in the outer edge portion of the clip 15.

The outer ends of the elongated spring members 7 and 8 are fastened to angular anchor clips 20 which are slidably adjustable along the side portions of the crib 6. Each of said clips 20 carries a clamp screw 21 whereby it may be secured in adjusted position in relation to the length of the crib.

The clip apertures 16 and 17 and the eye 14 all receive loosely the wire of the bottle-holding coil; hence the operator may "screw" said coil upwardly and downwardly in relation to its supporting means to adjust accurately the height at which the bottle is supported.

The upper end portion of the bottle-holding coil 5 is bridged by a bottle keeper consisting of a small tension coil spring 23 having an eye portion 24 at each end which fixedly engages the upper turn or convolution of the coil 5 at diametrically opposite points. This arrangement enables the operator to push the keeper 23 to one side preparatory to inserting a filled nursing bottle through the upper end of the coil 5 and then projecting its neck portion through the lower end of said coil to bring the nipple 11 within the reach of an infant lying in the crib. Then after

the bottle has thus been put into place said keeper spring may be brought back into a position wherein it diametrically bridges the upper end of the coil 5, the contractile nature of said keeper frictionally maintaining it in this adjusted position.

Mention has already been made of "screwing" the bottle-holding coil up and down in relation to its supporting means. As an additional means for adjusting the bottle's height each of the horizontal supporting springs throughout its outer portion surrounds a bendable rod 26 or 27, these rods being in any suitable manner united to or made integral with the clips 20, and the springs being secured in place preferably by being soldered to the clips 20.

From the foregoing description it will be seen that the bottle-supporting means afforded by this invention safely supports the bottle in a position wherein the infant has ready access thereto and yet said means is capable of a wide range of adjustment, for the clips 20 to which the elongated spring members 7 and 8 are anchored are adjustable along the sides of the crib to position the bottle at different points in regard to the length of the crib, the bottle-holding coil is vertically adjustable by being rotated or "screwed" up and down in relation to its supporting means and the soft metal bendable rods 26 and 27 may be deflected downwardly more or less in relation to the clips 20. The final part of the adjustment of the position of the bottle is best effected by rotating the coil 5 which contains it, in the manner which has already been described, for this latter adjustment enables the operator to adjust very accurately the elevation of the supported bottle. Also the resiliency of the device permits considerable lateral deflection of the nipple-carrying portion of the bottle.

Although the invention has been disclosed in relation to a baby's crib the device is equally adaptable for use with a baby's carriage or other perambulator.

It should be understood that the present disclosure is for the purpose of illustration only and that this invention includes all modifications and equivalents which fall within the scope of the subject matter claimed.

What is claimed is:

1. In a nursing-bottle support, in combination, a bottle holder and a pair of elongated extensible spring sections, each of said spring sections having one end attached to said bottle holder and its opposite end attachable to the side rail of a baby crib thereby to support a bottle above the bed portion of the crib, said bottle holder comprising a wire coil of sufficiently large diameter to contain the bottle, one of said spring sections being attached to one side of said coil and the other of said spring sections being attached to the diametrically opposite side of said coil, and a plate having through it a pair of apertures, said apertures each having a side run of said coil passing through it, one of said elongated spring sections being attached to said plate.

2. In a nursing bottle supporting means, a wire coil of sufficient diameter to contain within it and support a nursing bottle disposed with its axis extending axially of the coil, one end portion of the coil being contracted to surround closely the neck portion of the bottle, means to support the coil with its contracted end portion directed downwardly, the turn of the coil at the end thereof opposite to its said contracted end being of a sufficiently large diameter to admit the bottle, and a coiled spring member having an eye portion at each end attached to said coil and adjustable from a side-pushed condition in relation to said turn wherein a nursing bottle may be projected into said coil to a diametrically spanning relation to said turn thereof to keep in place a nursing bottle contained within the coil.

3. In nursing bottle supporting means, a wire coil of sufficient diameter to contain within it and support a nursing bottle disposed with its axis extending axially of the coil, and two supporting connections, one of said connections having an end portion loosely connected with one side portion of said coil and the other of said connections having an end portion loosely connected with the opposite side portion of said coil, whereby when said coil is suspended by and between said connections it may be rotated in relation to said connections thereby varying the height at which the bottle is supported by said coil.

4. Nursing bottle supporting means comprising a bottle holder, two elongated spiral springs having inner ends connected with opposite sides of said bottle holder, anchoring means to which the outer end portions of said springs are fastened, and a rod of soft bendable metal contained within the outer end portion of each of said springs, each of said rods having its outer end secured to said anchoring means.

5. In nursing bottle mounting means, a wire coil of sufficient diameter to contain within it and support a nursing bottle disposed with its axis extending axially of the coil, and supporting means for said coil mountable upon and between the side portions of a child's crib, said coil being screwable upwardly and downwardly in relation to said supporting means to adjust accurately the height at which the bottle is supported.
